UNITED STATES PATENT OFFICE.

HENRY W. STOKES, OF PHILADELPHIA, PENNSYLVANIA.

SURGICAL AND LIKE BANDAGE.

1,262,281.

Specification of Letters Patent.

Patented Apr. 9, 1918.

Application filed January 12, 1918. Serial No. 211,629.

To all whom it may concern:

Be it known that I, HENRY W. STOKES, a citizen of the United States, residing at Philadelphia, in the county of Philadelphia and State of Pennsylvania, have invented a certain new and useful Surgical and like Bandage, of which the following is a specification.

The principal object of the present invention is to provide a comparatively inexpensive, soft, light and strong bandage which may be absorbent or water-proof, as desired, and which is possessed of the advantages of textile bandages but is free from their defects and disadvantages.

A bandage embodying the invention consists of one or more plies of crape paper which is soft, pliable and otherwise well adapted for surgical use and which is capable of being readily prepared and rolled, in combination with one or more rows of stitches which impart to the crape paper the tensile strength necessary for a bandage.

The invention will be claimed at the end hereof but will be first described in connection with the embodiment of it chosen for illustration in the accompanying drawings forming part hereof and in which—

Figure 1, is a perspective view of a bandage embodying features of the invention.

Fig. 2, is an end view of the bandage drawn to an enlarged scale and somewhat diagrammatic in character, and

Fig. 3, is a diagrammatic end view of a two-ply bandage which can be considered as a modification of the invention.

In the drawings 1, is a strip of crape paper. In the manufacture of crape paper the fibers are heaped, mounted or ridged so that the paper is very soft and pliable. For the purpose in hand crape paper may be made without sizing or filling or adulterant and as near sterile and pure as possible. Crape paper made from wood pulp may contain traces of sulfur but for the purpose in hand that is not objectionable as sulfur possesses antiseptic properties. Crape paper may be absorbent and not water-proof although my bandage is not injured or deleteriously affected by any moisture to which it is exposed in its intended use. Crape

paper may be water-proof and when incorporated in my bandage the latter will withstand moisture and will exclude air to a greater extent. Bandages of the invention 55 may be cut from large webs of crape paper and crape paper does not present at the selvage edges loose fibers such as are present in textile bandages cut from a large textile web. Crape paper, while surprisingly well 60 adapted for use in bandages, lacks textile strength sufficient to enable it to be wound with the requisite degree of tightness. This I compensate for by the employment of rows of stitches, or more accurately, lines of sewing machine stitches 2, which impart to the crape paper an unexpected degree of strength. Since in the crape paper high places on one side are generally opposite low places on the other side, it is not unlikely that under tension the paper slightly 65 elongates without tearing and so refers the strain to the rows of stitches, or more accurately to the thread constituting the rows of stitches which is strong enough to resist the 70 pull, leaving the paper intact. There may be more than one row of stitching as indicated at 2^a, in Figs. 2 and 3, in which case there are three rows or there may be two rows of stitches as indicated at 2, in Fig. 1. 75

The number of rows of stitches is therefore not material. In Figs. 1 and 2, one ply of crape paper is shown but more than one ply may be used and this is indicated diagrammatically in Fig. 3, in which the plies are 80 shown as separated, whereas in fact they are in contact. Evidently the rows of stitching can be inexpensively applied and the strips of crape paper can be readily cut and folded into plies when desirable and the 85 bandages can be conveniently rolled.

What I claim is:

A bandage for surgical and like purposes consisting of a strip of crape paper elongatable by flattening its crimps without rupturing its web, combined with lengthwise ranging stitching relatively non-elongatable and to which the stress is referred as the crimps flatten in bandaging, substantially as described.

HENRY W. STOKES.
